COMBINATION WASH BASIN AND TOILET

David J. Jacoby, 1268 Fleetwood Road, Rydal, Pa. 19046, and Robert A. Leymann, 3031 Stiles St., Philadelphia, Pa. 19121

Filed May 1, 1969, Ser. No. 16,971

Term of patent 14 years

Int. Cl. D23—02

U.S. Cl. D23—49

FIG. 1 is a front perspective view of a combination wash basin and toilet embodying our new design;

FIG. 2 is a front elevational view thereof;

FIG. 3 is a top plan view thereof; and

FIG. 4 is a right side elevational view thereof.

We claim:

The ornamental design for a combination wash basin and toilet, substantially as shown.
